UNITED STATES PATENT OFFICE

EDWARD J. ABBE, OF CLEVELAND, OHIO, ASSIGNOR TO THE ELWELL-PARKER ELECTRIC COMPANY, OF CLEVELAND, OHIO, A CORPORATION OF OHIO

CONTROLLER

Application filed October 20, 1927. Serial No. 227,509.

This invention relates to electric controllers, preferably for use in moving structures, such as motor vehicles, electric cars, elevators, traveling cranes, and the like, and is concerned with improvements on the type of controller disclosed in Patent No. 1,073,397, issued to The Elwell-Parker Company, September 16th, 1913, the assignee of the instant application.

The object of the present invention is to provide an improved safety device, in association with a controller of the type referred to, for rendering the controller operable only when the attendant is in a normal operating position, the circuit being automatically broken if the attendant leaves that position, and the controller being unoperable until he returns.

A further object of this invention is to provide a controller that will prevent the direction of rotation of the motors from being reversed without the current being entirely cut off for a brief interval of time between the forward and reverse movements of the motor, thereby preventing serious damage to the controller, the motors and possibly the vehicle itself.

The invention comprises the means by which I carry out the above operations, as hereinafter more fully described and set out in the claims.

In the drawings, Fig. 1 is a side elevation on a reduced scale of a motor vehicle equipped with my controller and safety mechanism; Fig. 2 is a side elevation of my controller with part of the casing removed; Fig. 3 is a plan with the casing removed; Fig. 4 is a vertical longitudinal cross section along the lines 4-4 of Fig. 3; Fig. 5 is a vertical transverse cross section along the lines 5-5 of Fig. 3; Figs. 6 and 7 are details of the interlocking mechanism taken along the planes 6-6 and 7-7 of Fig. 5; Fig. 8 is a sectional detail of the safety mechanism taken along the lines 8-8 of Fig. 3; Fig. 9 is a detail of the parts shown in Fig. 8, but in different positions.

As shown in the drawings, 10 represents the casing of the controller in which is

mounted the acceleration or speed control barrel 11, and the direction control barrel 12, these having respective cooperating fingers 13 and 14. The barrel 11 is rigidly mounted on a shaft 15, and is insulated therefrom by the insulator 16. The shaft 15 is journalled in bearings 17 and 18 at the ends of the casing. This shaft extends through the casing and is provided with suitable means for manually rocking it, such as the lever 19. The reversing control barrel 12 is rigidly mounted on a sleeve 20 and is insulated therefrom by the insulator 21. The sleeve 20 is rotatably mounted on the right hand portion of the shaft 15. Rigidly mounted at the right hand end of the sleeve 20 is a member 22 and pivoted thereon is the lever 23, by means of which the barrel 12 may be manually rotated. The casing is slotted to permit the lever 23 to pass through it and the slot is provided with recesses 24, 24a and 24b, in which the operator may selectively seat the lever and thus variably position the barrel. A suitable spring, such as the spring 25, keeps the lever in contact with the recesses. The direction control barrel 12 has three operating positions as follows: When the lever 23 is in the slot 24a, its upper position, the circuit is such that when the motors are accelerated they will rotate to move the vehicle forwardly; when the lever is in its lowermost position, in slot 24b the circuit is such that the vehicle will accelerate backwardly; and when the lever 23 is in the intermediate slot 24, the circuit is broken and the rotation of the acceleration control barrel 11 will not affect the motors. The slots 24a and 24b are so shaped as to cooperate with the spring 25 in tending to main the lever 23 in its full "forward" and "reverse" positions.

To prevent the reversing of rotation of the motors while the barrel 11 is in an operating position, I provide the following mechanism: Between the two barrels I mount cams 30 and 31. The cam 30 is rigidly mounted on the shaft 15 and rotates with it, while the cam 31 is rigidly mounted on the sleeve 20 and rotates therewith. The cam 31 is provided with recesses 35, 36 and 37. Mounted in the casing is a shaft 40 on which are

pivotal mounted arms 41 and 42, each being free to move relative to the other. The arm 41 carries on its upper end a locking lug 43 so arranged as to engage with the recesses 35, 36 and 37 on the cam 31 when the barrel 12 is in its "forward", "off" and "reverse" positions respectively. The lower edge of the recess 35, and the upper edge of the recess 37, are beveled so that operation of the barrel, 10 while the locking lug 43 is in either of these positions will cam the lug outwardly and permit the barrel to rotate until the lug reaches the recess 36 where it will be locked against further rotation. To release the barrel 12 when in this locked position, I provide the roller 44 which is carried by the lug 43, (see Figs. 2, 5 and 6) and coacts with the cam 30 of the barrel 11. The cam surface 30 is so arranged as to cam the roller 44, and the 20 lug 43 outwardly to free the cam 31, only when the barrel 11 is in its "off" position. Hence, the barrel 12 can only be operated to reverse the direction of rotation of the motors when the accelerator control barrel 11 is in its "off" position. The arm 42 carries a roller 46 which coacts with recesses 47 in the cam 30 as detents to aid the operator to position the acceleration control. A spring 48 fastened to the levers 41 and 42 tends to 30 draw the arms toward each other to maintain the rollers 44 and 46 and the lug 43 in contact with the respective cams 30 and 31.

To make the operation of the controller dependent on the attendant being in proper position, I provide the following mechanism: Mounted in the controller casing is a vertical guide way 50 which carries a vertical shaft 51 provided with a key 58 to prevent its rotation. The shaft 51 is provided with a V 40 shaped head 52 at its upper end. The head has cam surfaces 53 adapted to coact with surfaces 54 of the member 22, as shown in Fig. 9, and cam the barrel 12 and the lever 23 to their intermediate or off position, as 45 shown in Fig. 8. The lower end of the shaft 51 is connected to a movable portion 59 of the supporting platform 60 by means of link 61, lever 62, link 63 and an arm 64 which projects rigidly from the movable portion of 50 the platform 59. Suitable springs placed anywhere in the mechanism, as indicated by springs 65 and 66 tend to move the mechanism in a direction to elevate the platform, and raise the head 53 to the position shown 55 in Fig. 8.

With the mechanism described, and when the operator is standing on the movable platform, the shaft 51 is drawn downwardly, withdrawing the head 52 from contact with the member 22, as shown in Fig. 9, permitting the operator to manually move the control lever 23 to position the barrel 12 for rotating the motor to propel the vehicle forwardly or backwardly as desired. If, how-

ever, the operator should remove his weight from the movable portion of platform with lever 23 in operating position, the shaft 51 will be forced upwardly by action of the springs 65 and 66 which will cause the head 52 to cam the barrel 12 to its "off" position, and lock it there, due to pressure of the springs until the movable platform 59 is again depressed by the operator being in position. Now, the circuit being open at the barrel 12, 70 it is immaterial if any one, tampering with the mechanism should turn the acceleration control barrel 11 to its active position. 75

Means are provided to return the acceleration control barrel 11 to its "off" position 80 when the operator takes his hand off the lever 19. The shaft 15 carries a lever 70 which is connected to a rod 71 by means of a link 72. On this rod is a head 73 which has a sliding connection with the yoke 74 which is pivoted to the frame of the vehicle. A compression spring 75 is interposed between the head 73 and the other end of the yoke 74. This tends to automatically return the shaft 15 and rotate the barrel 11 to its "off" position where 85 it is always urged against manual operation by the spring 75.

But suppose that when the operator leaves the platform the control lever 19 is jammed or for any reason the barrel 11 is in its "on" position instead of an "off" position as it should be under these circumstances, the locking lug 43 will fall into the recess 36 and lock the barrel 12 against rotation. Now, under these conditions when the movable platform 59 is 95 swung downward by the presence of the operator the head 52 will be withdrawn from contact with the member 22, but the barrel 12 cannot be rotated until the barrel 11 has first been turned to its "off" position and the cam 30 has carried the lug 43 out of contact with the recess 37 of the cam 31.

From the above description it will be seen that when the operator leaves the platform the direction control barrel is turned to an "off" position, regardless of the position of the acceleration control barrel and it is impossible to turn it to an operating position, unless the accelerator control be at "off" position, also that the operator cannot rotate the 105 direction control barrel from one operating position to another unless the acceleration control is first moved to an "off" position. Accordingly, my mechanism protects against tampering with the device when the operator 110 is off the platform as well as prevents the operator from doing serious harm to the motors without first bringing the controller to an "off" position.

It is also evident that the manually operated speed controller effects acceleration of the truck motors when the motors are running in either direction to drive the truck forward or backward, but it is only manually operated to turn the controller in one direc- 115 120 125 130

tion, that is, to effect increasing speeds of the motors. It is always urged in the opposite direction against manual exertion by a spring operated means which tends to return the speed controller to a starting position. Hence, when the hand is taken off the hand lever the speed controller is immediately urged to "off" position. In other words, the speed controller must be constantly manually controlled to keep the truck running, and the spring means will return it to "off" position. The direction controller can only be manually operated at automatically predetermined positions of the running controller. The automatic operation of the reversing controller to a neutral position is immediately effected upon the operator leaving his position on the platform of the truck.

The operator does not need to depart entirely from the truck to effect the automatic operation of the reversing controller to its neutral position, but merely shifts his weight to the fixed portion of the supporting platform, removing it from the movable portion, thus the operator can permit the automatic return of the reversing controller to neutral from either one of the reversing positions of the controller without leaving his position on the truck, and he can, if he desires, manually operate the direction controller from forward position to neutral and then to reverse position, but he cannot go through this cycle except with the acceleration control in neutral.

I claim:

1. The combination of an acceleration control barrel, a member movable therewith, a direction control barrel, a member movable therewith, and an integrally movable interlocking device arranged to operatively contact with both members, to prevent operation of the direction control barrel when the acceleration control barrel is in an "on" position.

2. The combination of an acceleration control barrel, a direction control barrel, and an interlocking mechanism disposed between the two barrels including an arm disposed between the two barrels controllably rocked by the acceleration control barrel and latchingly connected to the direction control barrel to prevent the movement of the direction control barrel from the "off" position until the acceleration control barrel is in an "off" position.

3. The combination of an acceleration control barrel, a cam member rotatable with the acceleration control barrel, and a member having a recess rotatable with the direction control barrel and disposed between the barrels, a roller coacting with the cam member, a locking lug associated with the roller and arranged to enter the recess in the recessed member when the direction control barrel is in the "off" position, the cam member being arranged to withdraw the locking lug when

the acceleration control member is in the "off" position.

4. The combination in a truck of an acceleration controller barrel, a direction control barrel, and means for operating them, of a movable operator's support, mechanism operating automatically to move the direction control barrel to an "off" position when the support is raised, and mechanism between the control barrels arranged to prevent the return of the direction control barrel to an operating position until the acceleration control barrel is in an "off" position.

5. In an electric controller for motor vehicles, a speed controller barrel manually operable in a speed acceleration direction and automatically operable in a speed reducing direction, a reversing control in connection with the speed controller, means for automatically shifting the reversing controller to a neutral or open position, and an interlocking means associated with the two controller mechanisms for predetermined the position of the speed controller at which the reversing controller can be shifted to either one of its line closing positions.

6. In an electric controller for motor vehicles, a speed controller manually operable in a speed acceleration direction, and automatically operable in a speed reducing direction, a reversing controller in connection with the speed controller, a movable operator's platform, means for automatically moving the reversing controller to an off position when the platform is raised, and means for predetermined the position of the speed controller at which the reversing controller can be shifted to either of its line closing positions.

7. In an electric controller for motor vehicles, a speed controller manually operable in a speed accelerated direction, and automatically operable in a speed reducing direction, a reversing controller manually operable to either of its line closing positions at a predetermined position of the speed controller, a safety member, a movable platform, and a connection between the platform and the safety member operating to move the reversing controller to an "off" position consequent on the raising of the platform.

8. In an electric controller for motor vehicles, a speed controller manually operable in a speed accelerated direction and automatically operable in a speed reducing direction, a reversing controller, manually operable in either of its line closing positions at predetermined positions of the speed controller only, a movable operator's platform, and a connection between the platform and the reversing controller to automatically move the reversing controller to an off position consequent on the raising of the platform.

9. The combination of an acceleration con-

trol barrel, and a direction control barrel mounted on a common shaft, locking mechanism disposed between the two barrels including a cam on the acceleration control barrel, and a member co-operating with the cam and carrying a locking device arranged to hold the direction control barrel in "off" position, said member being controlled in its position entirely by the cam to prevent rotation of the direction control barrel until the acceleration control barrel is in an "off" position.

10. The combination with a controller having an acceleration control member, a direction control member, and a movable safety device operating to move the direction control member to an "off" position whether the acceleration control member is in "off" or "on" position, and means positioned by the acceleration control member and directly engaging a rigid part of the direction control member for preventing the movement of the direction control member to an "on" position until the acceleration control member is in an "off" position.

11. The combination in an industrial truck of a controller having an acceleration control member and a direction control member, a movable platform arranged to support the weight of the operator, means for moving the direction control member to an "off" position consequent upon the platform being raised, and means preventing the movement of the direction control member from the "off" position until the acceleration control member is in an "off" position.

In testimony whereof, I hereunto affix my signature.

EDWARD J. ABBE.
